UNITED STATES PATENT OFFICE.

EDWARD P. VAN STONE, OF READING, MASSACHUSETTS, ASSIGNOR TO GENERAL ALLOYS COMPANY, OF BOSTON, MASSACHUSETTS, A CORPORATION OF MASSACHUSETTS.

BOX FOR USE AT HIGH TEMPERATURES.

Application filed April 7, 1927. Serial No. 181,719.

This invention relates to boxes which are to be subjected alternately to a high temperature and then cooled such, for example, as carburizing boxes.

5 Heretofore boxes of this general type have been made with the side walls and bottom as an integral casting, the open end being provided generally with a depression into which a cover could be fitted. Boxes made in this 10 manner had a relatively short life and soon developed cracks and warped due to the repeated heating and cooling, giving a differential in expansion and contraction. Other attempts have been made to make such boxes 15 with side plates secured by connected cast corner pieces, but such boxes have been found practically impossible to manufacture owing to the differential in expansion and contraction of the corner casting connections 20 on cooling and have been short lived because of the strains imposed on the parts thereby.

It is an object of the present invention to provide a box of this general type which will better resist the operating conditions and 25 strains encountered by alternate heating and cooling, and which is constructed to resist the strains and shocks of handling better than those now in use. This is accomplished in part in accordance with the invention by 30 providing a jacket open at opposite ends and, preferably, formed of a plurality of horizontally corrugated plates united by independent corner castings. If desired, the plates and the castings both may be corrugated and one or both of the open ends may 35 be closed by a removable plate.

The invention will be more clearly understood from the following description in conjunction with the accompanying drawings; 40 in which,

Fig. 1 is a plan view of a box embodying the invention; and

Fig. 2 is a sectional view taken upon the line 2—2 of Fig. 1.

45 In the drawings the invention is illustrated as an open ended body structure comprising a plurality of side plates 10 united at their juxtaposed edges by castings 11 of preferably uniform cross section to form 50 about the said edges, jackets or corner posts, the ends of which terminate substantially flush with the open ends of the body structure to provide a suitable continuous surface for engagement with closures such as 14.

55 It is an important feature of the invention

that the said castings or corner posts are independent of each other, except in so far as they are connected by the said plates 10, so that they are freely movable relative to one another with the expansion or contraction 60 of the said plates, and thereby do not impose such strain on the plates as would otherwise occur were the said corner posts connected such as by a cast bottom or frame.

It is preferred that the said side plates 10 be corrugated parallel with the open ends of the body structure as shown so as to strengthen the structure for handling purposes, but also to provide a definite tendency of the said plates to extend or contract in 70 the direction of their length and subject to changing temperatures in their normal plane, instead of bending under the influence of such changing temperatures and thereby imposing strains at their junctures 75 with the corner castings. Still further the presence of the corrugations assists the plates in adapting themselves naturally to expansion and contraction of the corner castings in the direction of the length of the 80 said castings. If desired, the connected end portions of each plate 10 may be provided with an irregularity such as openings 12 to permit the entrance of the metal of castings 11 thereto to form interlocking joints 85 therewith.

The closures 14 of the box are freely applied thereto so that they do not interfere with the expansion and contraction of the plates 10 and the consequent movement of 90 the castings 11 relative to one another so that the function of the independent castings is not interfered with.

It has been found in actual practice that carburizing boxes constructed in the manner 95 suggested have a much longer life than those wherein the welding of side plates to the frame is resorted to, resulting in, what amounts to practically an air chilled casting at such welding points, which includes those 100 parts of the plate immediately adjacent the weld, and it is further found that they do not suffer from the defects attending carburizing boxes in which the side plates are set in a frame wherein the corner posts are rigidly connected together as heretofore known. The importance of increasing the life of such boxes will be readily appreciated in view of the fact that heat resisting metals or alloys, 105 which it is necessary to use in the construc- 110

tion of such boxes, are expensive commodities, and where carburizing or similar operations are carried out, the expense of maintaining carburizing boxes is quite heavy.

5 This invention may be developed within the scope of the following claims without departing from the essential features of the said invention, and it is desired that the specification and drawings be read as being 10 merely illustrative and not in a limiting sense, except as necessitated by the prior art.

What I claim is:

1. In a box for use at high temperatures, an open ended wall structure comprising a 15 plurality of sheet metal side plates, and cast members connecting said plates, said members being independent of each other and freely movable with the expansion and contraction of said plates.
- 20 2. In a box for use at high temperatures, an open ended wall structure comprising a plurality of sheet metal side plates having corrugations parallel with the open ends of the said structure, and cast members connecting said plates, said members being independent of each other and freely movable with the expansion and contraction of said plates.
- 25 3. In a box for use at high temperatures, 30 an open ended wall structure including a plurality of sheet metal side plates, and cast members connecting said plates, said cast

members terminating substantially at the upper and lower edges of said plates and being independent of one another.

35

4. In a box for use at high temperatures, an open ended wall structure comprising a plurality of sheet metal side plates, cast members connecting said plates, said members being independent of each other, and 40 closures for the ends of said wall structure, said plates and said cast members being freely movable over the opposed surface of said closures.

5. In a box for use at high temperatures, 45 an open ended wall structure comprising a plurality of sheet metal side plates provided with surface irregularities near their juxtaposed edges, and cast members overlapping the said edges and interlocking with the 50 said surface irregularities.

6. In a carburizing box, an open ended wall structure comprising a plurality of sheet metal side plates provided with surface irregularities near their juxtaposed 55 edges, and cast members overlapping the said edges and interlocking with the said surface irregularities, said members being independent of each other and freely movable with the expansion and contraction of 60 said plates.

In testimony whereof I affix my signature.

EDWARD P. VAN STONE.
